BY *Victor J. Evans*

ATTORNEY

UNITED STATES PATENT OFFICE.

BARNEY A. COOKE, OF LINDSAY, CALIFORNIA.

RAZOR.

Application filed April 20, 1923. Serial No. 633,495.

To all whom it may concern:

Be it known that I, BARNEY A. COOKE, a citizen of the United States, residing at Lindsay, in the county of Tulare and State of California, have invented new and useful Improvements in Razors, of which the following is a specification.

This invention has reference to a razor of that class known as a safety razor, and has for its object to simplify, cheapen and improve the existing art by producing an article of this character in which a flat round blade is employed and which is supported adjacent to a thin guard attached 15 to the handle of the device, the said guard being round in plan and extended beyond the edge of the blade whereby the entire edge of the blade may be employed and the shaver protected by the guard from cutting himself.

With these and other objects in view the invention will be better understood from the following detailed description taken in connection with the accompanying drawing 25 wherein:—

Figure 1 is a side elevation of a razor in accordance with this invention.

Figure 2 is a sectional view on the line 2—2 of Figure 1.

Figure 3 is a sectional view on the line 3—3 of Figure 1, looking in the direction of the arrows.

Figure 4 is a plan view looking toward the blade.

Figure 5 is a plan view of the blade.

The handle portion 1 of the improvement is preferably round in cross section and is preferably integrally formed, at a slight distance from one of its ends, with radially 40 disposed flat spokes 2 formed on the inner periphery of a flat ring 3. The outer periphery of the ring is preferably rounded. The ring 3 provides a guard for the blade hereinafter described, and the slightly projected end 4, of the handle 1, outward of the ring serves as a spacer element for the blade.

The handle has a central longitudinally extending squared opening or bore.

The blade is indicated by the numeral 5 and is in the nature of a flat disk whose edge is, of course, sharpened. The blade has a squared opening 6 therethrough for the reception of the squared shank 7 that has one of its ends headed, as at 8 and its 55 opposite end rounded and threaded, as at 9. The head 8 is designed to contact with the outer face of the blade 5 and the reduced headed end 9 of the shank is engaged by a nut 10 which contacts with the outer end of the handle 1. By this arrangement it will be noted that the blade is effectively held against movement on the handle. The guard 3 is of a greater cross sectional diameter than that of the blade 5, and consequently the said guard has its edge projected a suitable distance beyond the cutting edge of the blade. The blade is spaced from the guard by the handle extension 4 so that ample cutting space is 70 provided between the guard and blade. Lather will seep between the blade and guard, passing through the spaces between the spokes 2, and it is thought that the foregoing description, when taken in connection with the drawing will fully set forth the construction and advantages of my improvement.

Having described the invention, I claim:—

In a safety razor, a handle having spokes radiating from a point close to one of the ends thereof, a ring to which the spokes are connected, said handle having a squared bore, a disc blade resting on the end of the handle adjacent to the ring and being of a less cross sectional diameter than that of the ring, said blade having a centrally squared opening, a headed member having a squared shank passing through the bore 80 of the handle and terminating with a threaded extension and a nut screwed on said extension to contact with the handle, for moving the shank longitudinally through the handle to cause the head thereof to bind against the blade.

In testimony whereof I affix my signature.
BARNEY A. COOKE.
